CHARLES BRAHY, OF STATEN ISLAND, NEW YORK, ASSIGNOR TO CHARLES E. MARION,
OF NEW YORK, N. Y.

STOP MECHANISM

Original application filed October 8, 1929, Serial No. 398,162. Divided and this application filed September 19, 1930. Serial No. 483,039. Renewed October 5, 1931.

This application is a division of my application for automatic liquid fuel dispensers filed October 8, 1929, Serial No. 398,162, the scope of this application covering improvements in mechanisms to effect the stoppage of operation of the apparatus to which this invention is attached.

An object of my invention is to produce a mechanism that will automatically terminate the cycle of operation of a machine, particularly one actuated by rotary driving means, such as the liquid fuel dispenser described in the above referred to parent application of which this is a division. Another object is to provide remote control stopping means, so that where the operation of a machine is controlled by remote means, as in the case of the pump and coin control mechanism disclosed in the said parent application, the machine will be caused to actuate the control mechanism at the end of its cycle of operation to bring about a stoppage of the apparatus. A further object of this invention is to provide a vapor proof construction for such electrical parts as may be subjected to sparking, so as to eliminate the danger of explosions due to the ignition of combustible vapors, such as generally abound in the vicinity of gasoline stations. Other objects and features will appear from the drawings, and the description hereinafter given.

Referring to the drawings:

Figure 1 is a fragmentary and partial sectional elevation of the circuit breaking tripper switch and tripping mechanism constituting part of my invention.

Figure 2 is an elevation of the solenoid actuated by the mechanism shown in Figure 1 and which is attached to the mechanism for starting and stopping the machine to which this invention is attached.

Figure 3 is a front sectional elevation of an automatic liquid fuel dispenser, showing the general arrangement of the apparatus embodying the stop mechanism constituting my invention.

In the drawings, the casing 10 contains the coin control mechanism, and the casing 11 the rotary driving means for actuating the machine, in this case the liquid fuel pump 12.

Mounted within casing 10 is the panel 13, to which is attached the coin chute 14, under the opening 15 of which is the temporary coin receptacle 16. This receptacle is adapted to swing downwardly under the weight of a coin, and thereby bring the machine into operation. The parent application of which this is a division contains a complete description of the mode of operation and of the coin control mechanism, and hence a detailed description thereof will not be repeated here. It should be observed, however, that after the coin is deposited and during the entire cycle of operation of the machine, the coin remains within the said receptacle 16, until the stop mechanism constituting my invention causes this receptacle to swing farther down until the coin is caused to drop through the chute 17 into the coin box 18. This operation, which will be hereinafter described, results in the breaking of the motor actuating circuit and in the consequent stoppage of the machine.

The casing 19 contains the circuit breaking solenoid 20, the core 21 of which is connected with the stem 22 through the coupling 23. Within the casing 11 is the driving means or gear wheel 25 to which is connected the pump connecting rod 26 and the tripping cam 27.

Mounted on the casing 11 is the bracket 28 which contains the tripper switch for setting into motion the circuit breaking mechanism. The lever 29, pivotally connected at 30, carries the roller 31 which is engageable with the surface of the tripper cam 27. Pivotally attached to the lever 29 is the rod 32, the helical spring 33 being mounted thereon and fixed thereto at 24. The rod 32 is pivotally attached to link 35 which is mounted on shaft 36. Connecting the ends of rod 32 and the contact bearing lever 37 is the spring 38, the said contact lever having thereon the protruding element or finger 39 adapted to engage the link 35, and the contact point 40 adapted to come into abutment with the contact 41.

When a coin is deposited into the coin deposit slot 42, it drops down through the coin chute 14 and into the temporary coin recep-

tacle 16. The weight of the coin causes the receptacle to swing down, bringing into abutment the contacts 43 and 44 to cause an electric circuit to actuate the motor 45 which, through a system of shafting and gearing, drives the gear wheel 25.

The gear wheel 25 is shown in its starting position. At the end of one complete revolution thereof when a fuel dispensing cycle has been completed, the surface 47 of the tripper cam 27 will strike the roller 31 and cause a clockwise movement of the lever 29 around its center 30, thereby producing a movement of the rod 32 in the direction of the arrow against the action of spring 38. This movement is transmitted through the spring 38 to the lever 37, resulting in the contacting of points 40 and 41. This closes the circuit through the solenoid 20, as a result of which the core 21 is drawn down, carrying with it, against the action of spring 48, the stem 22. This movement of stem 22 is transmitted to the receptacle 16 which is thus caused to continue on its downward swing to drop the coin through chute 17 into the coin box 18.

After the roller 31 passes over the apex 49, the lever 29 will move in a counterclockwise direction and cause the rod 32 to move to the right, so that the link 35 will engage the finger 39 and cause a clockwise movement of the lever 37, thereby separating the contacts 40 and 41. This breaks the circuit through solenoid 20, permitting the spring 48 to move the stem 22 upwardly and back to its starting position. This upward movement is transmitted to the receptacle 16 which is carried back to its starting position by certain balancing mechanisms fully described in the above mentioned parent application. The return of the receptacle 16 is accompanied by a disengagement of the contacts 43 and 44, whereby the motor actuating circuit is broken and the gear wheel 25 caused to stop.

It will be noticed that the coin control and motor actuating mechanism are contained within casings 10 and 19, whereas the pump driving gear 25 is housed within a separate and remote casing 11. In this way stoppage can be effected by remote control means, thereby providing a flexible and safe apparatus.

Another feature of this invention is the vapor proof housing around such electrical parts as may be subjected to sparking, so as to remove the danger of combustible gases such as gasoline vapor from the pump enveloping the control points, with consequent danger of explosions. Thus the casing 50 which contains the contacts 40 and 41 has no free and exposed openings through which combustible vapors can enter.

The particular form of apparatus disclosed in the drawings and in the description herein given, constitutes but one of several differ-

ent mechanical forms that can be embodied in my invention.

What I claim is:

1. A stop mechanism comprising, in combination, a cam secured to rotary driving means, a lever operable by said cam, a rod operable by said lever, a second lever, two adjacent contact points one of which is carried by said second lever, said rod being provided with a yieldable connection to said second lever, electro-mechanical means electrically connected with said contact points and provided with a movable element attached to motor-actuating means, means to keep said contact points normally disengaged, and means to bring said contact points into temporary abutment so as to momentarily close the circuit through said electro-mechanical means to actuate said movable element. 70

2. A stop mechanism comprising, in combination, a cam secured to rotary driving means, a lever operable by said cam, a rod pivotally connected to said lever, a second lever, two adjacent contact points one of which is carried by said second lever, said rod being provided with a yieldable connection to said second lever, yieldable means operable upon said rod and second lever so as to normally keep said contact points disengaged, said cam being adapted to actuate said first mentioned lever against the action of said yieldable means so as to cause the contacting of said points, a member pivotally attached to said rod and operable upon said second lever to cause the disengagement of said contact points, and electro-mechanical means electrically connected with said contact points and provided with a movable element attached to motor-actuating means. 80

3. In a stop mechanism a bracket having thereon a housing, a lever, two adjacent contact points one of which is carried by said lever, said lever and points being enclosed within said housing, a rod slidably extending through a hole in said casing, said rod being provided with a yieldable connection to said lever, yieldable means coacting with said rod and lever to keep said points normally disengaged, means operable upon said rod to bring said points into engagement, and a member connected to said rod and operable upon said lever to cause the disengagement of said points. 95

4. In a stop mechanism, a lever, two adjacent contact points one of which is carried by said lever, a rod provided with a yieldable connection to said lever, yieldable means coacting with said rod and lever to keep said points normally disengaged, means operable upon said rod to bring said points into engagement, said lever being provided with a protruding element, and a member connected to said rod and engageable with said element and cooperable therewith and with said 105

lever so as to cause said points to become disengaged.

5. In a stop mechanism a lever provided with a protruding element thereon, a pair of cooperable contact points one of which is carried by said lever, means operable upon said lever to bring said points into abutment, a member engageable with said protruding element and cooperable therewith and with 10 said lever to cause said points to become disengaged, and means to actuate said member.

6. In a stop mechanism a lever pivotally mounted on a shaft and provided with a protruding element thereon, a pair of cooperable contact points one of which is carried by said lever, a rod provided with a yieldable connection to said lever, a member one end of which is pivotally connected to said rod, the other end being mounted on said 20 shaft, means operable upon said rod and said lever to bring said points into abutment, the said member being engageable with said protruding element and cooperable therewith and with said lever to cause said points to 25 become disengaged.

7. In a stop mechanism, driving means, a lever, a pair of cooperable contact points one of which is carried by said lever, intermediate means yieldably connected to said 30 lever and adapted to effect the successive engagement and disengagement of said points, said lever having thereon a protruding element, a member engageable with said element and cooperable therewith to cause said lever 35 to move to a position where said points are disengaged.

8. In a stop mechanism, a cam secured to driving means, a lever, a second lever, a pair of coacting contact points one of which is carried by said second lever, intermediate means yieldably connected to said second lever and adapted to effect the successive engagement and disengagement of said contact points, the said cam and first mentioned lever coacting 45 to operate said intermediate means, a bracket, a housing positioned on said bracket and containing said second lever and said contact points, the said first mentioned lever being pivotally attached to said bracket.

50 In testimony of which I affix my signature.
CHARLES BRAHY.
